Atty.

UNITED STATES PATENT OFFICE.

JOHN T. McNIFF, OF WATERBURY, CONNECTICUT, ASSIGNOR TO RAYMOND F. McNIFF,
OF WATERBURY, CONNECTICUT.

BUSINESS-HOURS PLACARD.

1,423,485.

Specification of Letters Patent. Patented July 18, 1922.

Application filed February 19, 1921. Serial No. 446,238.

To all whom it may concern:

Be it known that I, JOHN T. McNIFF, a citizen of the United States, and a resident of Waterbury, in the county of New Haven 5 and State of Connecticut, have invented certain new and useful Improvements in Business-Hours Placards, which improvements are fully set forth in the following specification.

10 This invention relates to improvements in devices of that class available for displaying information to the public, and more particularly information regarding the opening and closing hours of stores, shops and other 15 mercantile establishments, such devices being well-designed business hours placards.

The object of this invention is to provide a placard of the character above indicated which shall be simple and inexpensive as 20 regards its construction; durable, efficient and dependable in practical service; convenient in its application to practical purposes; and which shall possess certain well-defined advantages over prior analogous 25 constructions.

The invention consists in the combinations, details and parts to be hereinafter more fully referred to and set forth in the 30 claims hereto appended, and whereby the attainment of the foregoing object is rendered practicable.

The invention is clearly illustrated in the accompanying drawing, wherein:

Fig. 1 is a front face view of a business 35 hours placard embodying my said improvements, the initial contextual tab thereof lying in registry with the plane of the body thereof.

Fig. 2 is an edge view of same, the initial 40 contextual tab thereof swung forwardly and downwardly to cover the upper margin of the body thereof.

Fig. 3 is a rear face view of the device, the final contextual tab thereof lying in 45 registry with the plane of the body thereof.

Fig. 4 is a detail face view, showing a fragment of the transverse annulling shield made use of.

In a general sense my present invention 50 embodies a body of card-board or the like, bearing general readable matter setting forth more particularly the hours or period of time between or during which the user's store, office, shop, or the like shall be open 55 for business or closed against business, and

including a plurality of contextual tabs, or the like, whereby a portion of said general matter may be temporarily annulled and replaced by other specific matter readable into the context of said general matter, said body 60 being further fitted with hour-indicating means and suitable tab-holding elements.

In carrying out my present invention, reference being had to the accompanying drawings wherein similar reference-characters denote like parts throughout the several views, I make use of a body 2 of card-board or the like, and bearing general readable matter, such as "This store will open at 8:30 A. M. Close at," said general matter being 65 followed by a suitable hour-indicating medium, as the dial 3 and pointers 3' 3'', shown in the accompanying drawing.

The pointers 3' 3'' are shiftable on a centering pivot 4, each independently of the other and under finger-pressure duly applied thereto and into indicating registry with the respective hour-indicating characters afforded by the dial 3; and there is further provided at the front face of the body 70 80 aforementioned and for rotative action on or relatively to the pivot 4, a minor blinder 5, whose function, when duly manipulated, is to temporarily annul—as A. M., P. M., or A. P. M., borne by said body at the medial 85 segment thereof covered or coverable by said shield.

Said body is further provided with opposite tab-holding clips 5', 5'', whereby is detachably held transversely of the body, a 90 medial annulling shield 6.

The back face of the body 2 bears general readable matter, such as "To-day being a 95 holiday this store. (or as the case may be), will be closed all day."

I further provide a group of contextual tabs 7, loosely attached as a group to the body 2, preferably at the top margin thereof and preferably by means of interlinking or attaching rings 8, each of the tabs comprised 100 in the group thereof aforementioned, being reversibly shiftable, through the medium of said rings, in a manner to cause the same to traverse either the top front, or top rear, margin of the body 2 and thereby serve to 105 temporarily annul that portion of the general readable matter borne by the top body margin so traversed by such tab.

The contextual tabs aforementioned serve 110 each, not only to annul the general readable

matter borne by the top margins of the body 2, as above explained, but to replace such annulled general readable matter with certain specific readable matter,—as "Saturday next", "Wednesday, Clerks' Half Holiday", etc.,—contextually readable into the general readable matter borne by the body 2 at either face thereof, said specific readable matter being borne, respectively, by any appropriate number of the contextual tabs comprised in the general group thereof, and at either face, or both faces of each thereof, accordingly as the body 2 shall be provided at either face, or both faces thereof, with general readable matter, as will be readily understood.

It may be found desirable at times to alone annul certain of the general readable matter—as, "At 8:30 A. M., Closed",—borne, in this instance, by the body 2 at the front face thereof, and next following the readable matter borne thereby at the top margin thereof; and to facilitate the attainment of this end, I provide a transverse annulling shield 6, suitably notched at its opposite ends and so rendered capable of being brought endwise into temporary holding engagement with the shield-holding clips 5', 5".

With respect to the practical application of my improved placard, it may be stated, illustratively, that, where the readable matter borne by the body 2 suits, without change, the requirements of the user, his closing hour may be indicated on the dial 3 by setting the pointers 3', 3", accordingly, as in common practice, the minor blinder 5, however, being shifted on the pivot 4 in a manner to cover the abbreviations indicating forenoon, afternoon, or noon, positioned within the field coverable by said blinder, and as required by the user.

Again where certain of the readable matter intervening between the dial 3 and that borne by the top margin of the body 2 is to be annulled, shield 6 is made use of as above explained, and in conjunction with the dial and pointers and the minor blinder 5 of the device, as also above explained.

Still further, where the matter borne by the body 2 at its top margin, at either face thereof, is to be annulled, or annulled and replaced by specific matter, that contextual tab 7 bearing at its reverse face such specific matter to be used, is swung, separately, or together with more or less of the remaining tabs, and through the medium of the rings 8, into place at and in registry with such top margin of the body 2, and so that the specific matter carried thereby shall be readable contextually into the

general matter carried by said body below its said top margin, the dial, pointers and blinder aforesigned, respectively, being availed of, or not, as occasion may make 65 needful or desirable.

It will be seen that my improved placard is well adapted for the purposes for which it is intended, and further that the same may be modified to some extent without materially departing from the spirit and principle of my invention as set forth in and coming within the scope of the claims hereto appended.

Having thus described my invention, I 75 claim:

1. A business hours placard comprising solely a flat body formed from card-board and having arranged thereon general readable matter, and a plurality of contextual tabs, the latter conjoined collectively by means of metallic rings with said body for a free swinging movement upwardly over and beyond the uppermost margin thereof, and bearing, respectively, specific readable 85 matter readable contextually into the general readable matter aforesigned when caused, separately or more or less collectively, to traverse and overlie the upper portion of that face of the body bearing such general 90 readable matter.

2. A business hours placard comprising solely a flat body formed from card-board and having general readable matter arranged thereon at its opposite faces, and a 95 plurality of contextual tabs, the latter conjoined collectively with said body for a free swinging movement upwardly over, in either direction, and beyond the uppermost margin thereof, and bearing, respectively, specific 100 readable matter readable contextually into the general readable matter aforesigned, when caused, separately or more or less collectively to traverse and overlie the upper portion of either face of said body. 105

3. A business hours placard comprising solely a flat body formed from card-board and having general readable matter arranged thereon at its opposite faces, and a plurality of contextual tabs, the latter conjoined collectively by means of metallic rings with said body for a free swinging movement upwardly over, in either direction, and beyond the uppermost margin thereof, and bearing, respectively, specific readable 110 matter readable contextually into the general readable matter aforesigned, when caused, separately or more or less collectively, to traverse and overlie the upper portion of either face of said body. 115

JOHN T. McNIFF.
